UNITED STATES PATENT OFFICE.

EDMUND COURTNEY AND PAUL BORNHORN, OF COVINGTON, KENTUCKY.

HORSESHOE-CALK.

No. 873,119.

Specification of Letters Patent.

Patented Dec. 10, 1907.

Application filed August 5, 1907. Serial No. 387,052.

To all whom it may concern:

Be it known that we, EDMUND COURTNEY and PAUL BORNHORN, citizens of the United States of America, and residents of Covington, county of Kenton, State of Kentucky, have invented certain new and useful Improvements in Horseshoe-Calks, of which the following is a specification.

The object of our invention is a horse shoe 10 calk which may be readily secured upon a horse shoe and firmly locked thereon so that it will not be loosened by the horse's tramping upon hard, rough ground, and which is of a shape to give the most support to the 15 animal against slipping. This object is attained by the means described in the specification and illustrated in the drawings, in which,

Figure 1 is an inverted plan view of a horse 20 shoe of ordinary construction, supplied with horse shoe calks embodying our invention. Fig. 2 is a detail view of the ridge or stud of the calk and its integral lug of the form of calk which is secured to the heel of the shoe, 25 the view being taken from the interior of the shoe. Fig. 3 is a view similar to Fig. 2, but showing the jaw, screw and lock-nut in place. Fig. 4 is a sectional view taken upon line $x-x$ of Fig. 1. Fig. 5 is a detail perspective view of the inner jaw of the calk 30 illustrated in Figs. 2-4. Fig. 6 is a view similar to Fig. 4 of the form of calk secured to the toe of the shoe. Fig. 7 is an end view 35 of the calk secured to the toe, the view being taken from the interior of the shoe. Fig. 8 is an inverted plan view of a form of calk supplied with a rubber hob. Fig. 9 is a detail view of the lug and the hobs of the form 40 illustrated in Fig. 8. Fig. 10 is an interior elevation of a modified form of plate and screw.

Referring to the heel calk illustrated in Figs. 1-4: The ridge or stud, a , of the heel calk is formed integral with an upwardly 45 projecting flat jaw, a' , which terminates at its upper end in a detent, a^2 , which takes over the outer edge of the shoe, B. The ridge or stud, a , has V-shaped ways, a^3 , a^4 , formed upon its sides and has a central in- 50 teriorly screw-threaded recess, a^5 . A jaw, C, to coöperate with the jaw, a' , is formed from a flat plate having inwardly projecting arms, c , c' , to enter ways, a^3 , a^4 , and a perforation, c^2 , to register with the recess, a^5 . 55 A square headed screw, D, passes through the perforation, c^2 , and engages the threads

of the recess, a^5 . Between the head of the screw and the jaw, C, a lock-nut, c^3 , is placed. When it is desired to engage the calk with the shoe, the jaw, C, is separated from the jaw, 60 a' , a distance sufficient to pass the shoe, B, between the detents. Then the jaw, a' , is placed so as to contact the outside of the shoe, B, the jaw, C, taking over the interior periphery of the shoe. Then the screw, D, is 65 turned so as to carry the jaw, C, toward the jaw, a' , the arms, c , c' , moving along in the ways, a^3 , a^4 . After the calk has been secured in place, an extra turn is given to the screw so that the lock-nut, c^3 , will be jammed 70 against the face of the jaw, C, to prevent accidental unlocking of the same. In this form it is noted that the arms fitting in the ways, a^3 , a^4 , and the screw taking into the central recess, hold the jaws in rigid fixed 75 relation to each other so as to prevent any play therein which will keep the screw from working loose, an effect which is heightened by the operation of the lock-nut.

The form illustrated in Figs. 6 and 7 is 80 similar to that just described, with the exception that the keel, a^6 , is placed in a position parallel to the jaws, a' , instead of being transverse thereto, as in the form shown and described in Figs. 2-4, and in place of 85 having ways, a^3 , a^4 , recesses a^7 , a^8 , are made in the keel plate, into which the arms, c^4 , of the plate, C', take.

In the form illustrated in Figs. 8 and 9, the outer jaw, a' , is formed integral with a 90 horizontal plate which has projections, a^9 , a^{10} , upon each side, to which rubber hobs, E, E', are secured by screws, e, e'. The jaw, C', with its arms, c^4 , is the same as that illustrated in Figs. 6 and 7, the screw entering 95 the central interior screw-threaded recess, a^{11} , and the arms entering recesses, a^{12} , a^{13} .

In the modification illustrated in Fig. 10, all the parts are the same as illustrated in Figs. 2-6, except that in the plate, C², which 100 corresponds to the plate, C, the central perforation, c^5 , is enlarged and the plate has upon one side a cutaway portion, c^6 , from which a bore extends inward to the perforation, c^5 . A spring, c^7 , is secured at c^8 , to the 105 plate and has a pin, c^9 , projecting in through the bore in the plate, C². Screw, D', has formed upon it a collar adjacent to its head, in which are cut teeth, d, which are engaged by the pin, c^9 . When the screw is screwed into 110 place in the recess, a^5 , the teeth being faced so that while the pin, c^9 , permits the rotation

of the screw to pass it into the recess, a^5 , the said pin prevents the reverse rotation of the screw, thus guarding against accidental loosening of the screw. When it is desired 5 to remove the screw, it is necessary to hold the spring, c^7 , outward, so that the pin, c^9 , is out of engagement with the teeth, d .

What we claim is:

1. In a horse shoe calk a plate carrying 10 one or more studs for contacting the ground and a jaw for engaging one side of a shoe, the said plate having transverse ways and a screw-threaded recess, in combination with a second jaw having arms to engage the ways 15 and a perforation to register with the recess and a screw for passing through the perforation in the second jaw into the recess in the plate.
2. In a horse shoe calk a plate carrying 20 one or more studs for contacting the ground and a jaw for engaging one side of a shoe, the said plate having a screw-threaded recess,

in combination with a second jaw having a perforation to register with the recess, a screw to pass through the perforation in the 25 second jaw and into the recess in the plate, ratchet teeth near the head of the screw and a pawl mounted upon the said plate for engaging the ratchet teeth to prevent the screw's working loose. 30

3. A horse shoe calk consisting of a stud having formed integral with it a longitudinal jaw adapted to engage the exterior rim of a shoe and having a central screw-threaded recess and transverse ways in combination 35 with a second jaw, having arms to engage the ways and a central perforation to register with the recess, and a screw for passing through the perforation and into the recess.

EDMUND COURTNEY.
PAUL BORNHORN.
